UNITED STATES PATENT OFFICE.

CLARENCE W. RIEGEL, OF EASTON, PENNSYLVANIA, ASSIGNOR TO GENERAL CHEMICAL COMPANY, OF NEW YORK, N. Y., A CORPORATION OF NEW YORK.

CARBOY-PACKAGE.

1,380,020.

Specification of Letters Patent. Patented May 31, 1921.

Application filed November 22, 1920. Serial No. 425,622.

To all whom it may concern:

Be it known that I, CLARENCE W. RIEGEL, a citizen of the United States, and resident of Easton, county of Northampton, State 5 of Pennsylvania, have invented certain new and useful Improvements in Carboy-Packages, of which the following is a specification.

My invention relates to carboy packages 10 of the type in which the body of the carboy is inclosed in a container generally made of wood and provided in its top with an aperture through which the neck of the carboy protrudes. The object of my invention 15 is to provide a carboy package of this class in which the protruding neck of the carboy is adequately protected against breakage in a novel and improved manner and so as to preserve the general rectangular lines of 20 the package to facilitate storing and shipping thereof. Other more specific objects of my invention will appear from the description hereinafter, and the features of novelty 25 will be pointed out in the appended claims.

Reference is to be had to the accompanying drawings which illustrate an example of my invention without defining its limits and in which Figure 1 is a perspective view 30 of the carboy package; Fig. 2 is an elevation thereof; Fig. 3 is a sectional elevation on the line 3—3 of Fig. 2; and Fig. 4 is a horizontal section on the line 4—4 of Fig. 3.

In its illustrated example, the carboy package comprises the customary container 35 5 of rectangular form and constructed of any suitable material such as wood and provided interiorly with reinforcements in the form of corner posts 6. The latter are preferably of triangular cross-section so as to fit 40 into the corners of the container 5 and may be provided with spaced resilient strips 7 arranged to bear against the body of the carboy 8 to maintain the same in a relatively fixed position within the container. The 45 top 8^a of the container 5 is constructed in two complementary sections and is provided with the customary aperture 9 through which the neck 10 of the carboy protrudes as shown in Figs. 1 and 3. The container 5 50 may further be provided with exterior strips 11 secured along opposite sides thereof and undercut to afford a means for readily lifting the package. As so far described, the carboy package may be of any suitable and

well known construction and may include 55 any features customarily found therein.

As shown in Figs. 1 and 3, the corner posts 6 are continued upwardly beyond the top 8^a of the container 5 to form extensions 6^a which are preferably connected at 60 their upper free ends by means of cross-pieces 12. Similarly, two opposite side walls of the container 5 are continued upwardly beyond the top 8^a as shown at 5^a and are nailed or otherwise secured to the extension 6^a of the corner posts 6. The carboy package further includes a cover 13 which is located in spaced parallel relation to the top 8^a and as shown in the illustrated example, may be hinged at 14 to one of the 70 cross-pieces 12 and in such case may be provided with a locking means 15 of any conventional form or which may be fastened in place by means of nails, screws or other similar fastening devices. My improved 75 carboy, as will be seen from the drawings, therefore comprises the usual container for the carboy and a continuing superstructure which may be closed at two sides and open 80 at two sides to permit pouring out of the 80 contents of the carboy 8. This superstructure, by extending over and about the neck 10 of the carboy, protects it against impacts, blows and the like and consequently reduces 85 the possibility of the breakage of said neck 85 or injury thereto to a minimum; at the same time, the arrangement of the superstructure is such as to preserve the general rectangular form of the carboy package. As a result 90 of this, all exposed surfaces of the carboy package are flat so that it is possible to efficiently store and ship my improved carboy packages in a minimum of space and in an even and uniform manner. At the same time, the carboy package is eco- 95 nomical and may be produced without the assistance of any specially skilled labor in its construction. To refill the carboy, it is simply necessary to swing the cover 13 to an open position if the same is of the hinged 100 type or to remove it from the carboy package by withdrawing the nails, screws or other fastening devices hereinbefore referred to.

Various changes in the specific construction shown and described may be made within the scope of the claims without departing from the spirit of my invention. 105

I claim:

1. A carboy package comprising a container for a carboy and provided in its top with an aperture through which the neck of the carboy is arranged to protrude, reinforcing members extending lengthwise of said container and continued upwardly beyond its top, members secured to said reinforcing members to form upward continuations of the upright walls of said container and a cover extending over the ends of said reinforcing members in spaced, parallel relation to the top of said container.
2. A carboy package comprising a rectangular container for a carboy and provided in its top with an aperture through

which the neck of the carboy is arranged to protrude, interior corner posts located in the corners of said container and continued upwardly beyond the top thereof, cross-pieces connecting the continuations of said corner posts in pairs, members secured to said continuations of the corner posts to form upward continuations of two opposite side walls of the container and a cover hinged to one of said cross-pieces and arranged to lie over the free ends of said corner posts in spaced, parallel relation to the top of said container.

In testimony whereof I have hereunto set my hand.

CLARENCE W. RIEGEL.
